Inventor
H. B. Crandall,

UNITED STATES PATENT OFFICE.

HOSEA BALLOU CRANDALL, OF BROCTON, NEW YORK.

APPARATUS FOR CUTTING VENEERS.

SPECIFICATION forming part of Letters Patent No. 357,181, dated February 8, 1887.

Application filed July 23, 1886. Serial No. 208,874. (No model.)

To all whom it may concern:

Be it known that I, HOSEA BALLOU CRANDALL, a citizen of the United States, residing at Brocton, in the county of Chautauqua and State of New York, have invented a new and useful Improvement in Apparatus for Cutting Veneers, of which the following is a specification.

My invention relates to appliances for cutting 10 veneers for fruit boxes, baskets, and other similar purposes; and the object of my invention is to produce an apparatus whereby the veneers shall be rapidly cut into the required lengths for the boxes, baskets, or other articles, by means of which, also, the cutting shall be clean and accurate and free from any injury to the veneers.

To the above purposes my invention consists 20 in an oblong box or frame for holding the veneers, having open ends and guides on its inner sides, and also an upwardly-curved bottom, as hereinafter described and claimed.

The invention further consists in a peculiarly-constructed knife for cutting the veneers 25 adapted to work between the said guides, as hereinafter described and claimed.

My invention further consists in certain peculiar and novel features of construction and arrangement, as hereinafter described and 30 claimed.

In order that my invention may be fully understood, I will proceed to describe it with reference to the accompanying drawings, in which—

Figure 1 is a side elevation of the box or frame. Fig. 2 is a plan view of the same. Fig. 3 is an end elevation of the same. Fig. 4 is a perspective view of the cutting-knife.

In the said drawings, A designates the bottom of the box or frame; B, its two sides; and C, two foot-boards, which extend along the outer sides of the side pieces, B, as shown.

At each end the bottom A is inclined upwardly, as shown at a, for a purpose to be hereinafter described, and the side pieces, B, are suitably secured to the sides of the bottom A, as shown.

Upon the inner sides of the side pieces, B, are secured a series of vertical guide-strips, b, 50 the lower ends of which are interposed between the side pieces and the sides of the bottom.

These guide-pieces b are arranged exactly opposite to each other, so that the spaces between each opposite pair of strips shall also lie exactly opposite to each other.

55

D designates the cutting-knife, the blade d of which is of oblong rectangular form and of greater length than the distance between the upper side of the bottom A and the tops of the side pieces, B. The blade d is confined between two frame-pieces, d', which have grooves to receive the sides of the blade, and the blade is held securely in said frame-pieces by pins d'', as shown. At their upper ends the frame-pieces d' are reduced and threaded, as shown 60 at d'', to pass through the handle d' and receive nuts d'', by means of which latter the handle is secured to the frame-pieces. The lower edge of the cutter is beveled, as shown at d''. The box is placed in front of the veneer-machine, 70 and as the veneers are fed therefrom they run into the box, one above the other, till the box is full. The inclined ends of the bottom A raise the ends of the veneers, so as to overcome the settling of their tops, due to the fact that 75 some of the pieces of veneer are shorter than the box. After the box has been filled with the veneers the operator takes the knife, holding it with its bevel d'' toward him, and forces it downward in the opposite guide-spaces, cutting off the veneers, and, by virtue of the action of the bevel d'', forcing the severed pieces asunder, so as to prevent binding of the knife. As the operator works he stands astride of the box A upon the foot-board C, and passes 80 thus along the full length of the box, cutting at such intervals as may be required.

By this method two successive handlings of the stuff are avoided and a great saving in time is effected.

90

Having thus described my invention, what I claim as new, and desire to secure by Letters Patent, is—

1. The combination, with the bottom A, having the inclined ends a, of the sides B, having 95 the grooves or ways, and the cutter working in the grooves or ways, as set forth.

2. In an apparatus for cutting veneers, the box or frame having the parallel sides, the space between the sides being entirely open at the top, said sides being provided with a plurality of grooves or ways open at the top, and 100

a vertically-movable cutter designed to be inserted into the top of any one of the grooves or ways of the sides and extend across the space between the sides, as set forth.

5 3. In an apparatus for cutting veneers, the combination of an open-ended box or receptacle comprising the vertical parallel sides having the vertical grooves or ways in their opposing faces, and the bottom, to which the 10 sides are rigidly affixed, having the elevated portions *a* on its upper side arranged between the ends of the vertical sides of the box, and a vertically-movable cutter working in the vertical grooves of the sides, substantially as de- 15 scribed, for the purpose set forth.

4. In an apparatus for cutting veneers, the combination of an open-ended box or receptacle having the sides provided with the grooves

or ways and a vertically-movable cutter working between the parallel sides in the grooves 20 thereof, and comprising the grooved side bars having the threaded upper ends, the flat blade fitted and secured in the grooves of the side bars, a transverse handle-bar having the openings through which are passed the threaded 25 ends of the side bars, and the nuts for securing the side and transverse bars together, substantially as described, for the purpose set forth.

In testimony that I claim the foregoing as my own I have hereto affixed my signature in 30 presence of two witnesses.

HOSEA BALLOU CRANDALL.
